(57) **CLAIM**

The ornamental design for a display screen with graphical user interface for a messaging application, as shown and described.

DESCRIPTION

The FIGURE is a front view of an image of a display screen with a graphical user interface for a messaging application. The broken lines show portions of the graphical user interface that form no part of the claimed design. The outer rectangle in broken lines is included to illustrate a portion of a display screen and forms no part of the claimed design.

1 Claim, 1 Drawing Sheet
